UNITED STATES PATENT OFFICE

170,430

BIB OR SIMILAR ARTICLE

Leo Rudin, Passaic, N. J.

Application November 8, 1952, Serial No. 22,198

Term of patent 7 years

(Cl. D3—26)

To all whom it may concern:

Be it known that I, Leo Rudin, a citizen of the United States and a resident of Passaic, county of Passaic, and State of New Jersey, have invented a new, original, and ornamental Design for Bib or Similar Article, of which the following is a specification, reference being had to the accompanying drawing, forming part thereof.

In the drawing:

The figure is a plan view of a bib embodying my design.

I claim:

The ornamental design for a bib or similar article, substantially as shown.

LEO RUDIN.
